MECHANICAL KEY BOARD PLAYER.

No. 429,419.

Patented June 3, 1890.

UNITED STATES PATENT OFFICE.

EMIL CAPITAINE, OF EILENBURG, GERMANY.

MECHANICAL KEY-BOARD PLAYER.

SPECIFICATION forming part of Letters Patent No. 429,419, dated June 3, 1890.

Application filed October 3, 1889. Serial No. 325,905. (No model.)

To all whom it may concern:

Be it known that I, EMIL CAPITAINE, of Eilenburg, Germany, a citizen of Germany, have invented certain new and useful Improvements in Automatical Music-Instruments, of which the following is a specification.

This invention relates to an improved device to be attached to or upon key-instruments for the purpose of operating or playing the same by means of a slotted or perforated sheet or strip or disk.

The object of my invention is to provide a device of this kind which can easily be attached to the instrument and by means of which any desired melody can be played perfectly on any key-instrument.

The invention consists in the construction and combination of parts and details, as will be fully described and set forth hereinafter, and finally pointed out in the claims.

In the accompanying drawings, Figure 1 is a vertical transverse sectional view of one construction of my improved attachment for playing key-instruments. Fig. 2 is a detail top view of the key-presser. Fig. 3 is a detail longitudinal sectional view of a modification of the same. Fig. 4 is a vertical sectional view of the device for raising and lowering the key-presser. Fig. 5 is a vertical longitudinal sectional view of my improved playing attachment, the same being mounted to pass into the casing of the key-instrument. Fig. 6 is a sectional plan view of the same. Fig. 7 is a vertical transverse sectional view of the same.

Similar letters of reference indicate corresponding parts.

My improved playing attachment can be arranged in two different ways, either to depress the outer ends of the keys, and in that case the mechanism is arranged above the key-board and outside of the same, or the device can be arranged to raise the inner ends of the key-levers, and then the device is arranged below the keyboard. Both constructions in general are the same, and only differ some in details and the manner of application. In the construction in which the mechanism is above the keys said mechanism is placed into a casing A, supported by legs

B, which may be provided with devices for raising and lowering them, which devices are not shown and may have any desired construction. To plates b b' on a transverse rail B², extending across the top of the casing, a series of angle-levers a are pivoted in line in such a manner that one shank of each lever projects from the underside of the transverse rail B² and a beveled spring or toe a' on the end of the other shank of each lever projects above the tops of the plates and can be acted upon by the perforated or slotted music-sheet C, which rests upon and slides over the plates b b' and is wound upon a roller D, suitably mounted in bearings on the casing A, and from which roller it can be unwound upon another and similar roller upon the opposite end of the casing, the latter roller not being shown. The levers a pass through suitable slots in the rail B². The levers a are arranged in two groups, and between the same a wheel q is mounted, from the rim of which a series of teeth g' project, that can enter apertures arranged in a longitudinal row on the music strip or sheet C. Said wheel q is fixed on a suitable shaft q', journaled in the casing A, and said shaft and wheel are driven by means of suitable beveled gearing p' from a shaft p, on one end of which a crank or key or any other suitable device for rotating it can be applied. The inner end of each downwardly-projecting shank of the lever a is connected by a pull-rod f with the crank end f³ of a wire or rod f', mounted to turn in suitable bearings or sleeves on the under side of the plate A³ of the casing A, which wire or rod f' is provided on the ends opposite the ones provided with the crank f³ with a crank-arm f², that can act on the upper end of a screw g on a lever h, pivoted between suitable jaws of a rail C², arranged in the casing below the horizontal partition A³ and extending in the direction of the length of the apparatus. On the opposite end of each lever h a spring h³ acts, which is fixed in the casing or on suitable rod in the same and serves to press down one end of the lever h, thereby pressing the head on the screw g against the corresponding crank f². To that end of the lever h on which the spring h³ acts a friction-lever k is pivoted, which is provided on its lower end with a seg-

mental friction-surface k' , that can rest upon and be actuated by a friction-roller E, mounted in the casing A and parallel with the front of the key-board, which friction-roller E is rotated by the shaft p or driving mechanism of the same by means of a belt W². (Shown in dotted lines in Fig. 6.) The friction-lever k is provided with a fixed arm i, to which, at m, is pivoted one end of an angle-lever l, pivoted 10 to suitable jaws on the lower end of a screw-block K', into the threaded aperture of which a screw K is screwed, the upper end of which screw is mounted to turn in a socket A⁵ in the top of the casing A, said screw being provided above the socket with a squared end, on which a key M can be applied for turning said screw, and thereby raising and lowering the screw-block K', and thus adjusting the angle-lever l in relation to the corresponding 15 key F. On that end of the lever l adjacent to the key a clip L is fastened by means of two screws n, of which the inner one is passed through a slot n' of the said clip, thus permitting of adjusting said clip laterally, so that 20 the free end of the same will be directly above the center of the key. On said free end of the clip L a downwardly-projecting key-presser l' is fastened, which is preferably provided with a felt or leather head.

30 If desired, the key-presser l' can be secured on the end of a bent lever L², the opposite end of which is passed through an aperture in the lever l, which lever L² can be adjusted laterally on the end of the lever l and locked in 35 the desired position by means of the nut n², as shown in Fig. 3.

The operation is as follows: As long as the music-sheet C, which is held on the transverse rail B² by a suitable lever W, acts on the beveled ends or prongs a' of the levers a and 40 holds them down the inner ends of said levers a are raised and the cranks f² are bent down and press down the screws g and levers h, whereby those ends of the levers h on which 45 the springs h³ act are raised and are also the friction-levers k, and their friction-surfaces are not in contact with the friction-roller E, which rotates in the direction of the arrow x'. As soon as the beveled prong or toe a' of a 50 lever a arrives at a slot or aperture in the music-sheet it snaps upward, the corresponding spring h³ presses down the corresponding lever h, and the friction-surface of the corresponding friction-lever k is brought in contact with the friction-roller E and swung in 55 the same direction as the arrow x', whereby that end of the lever l connected with the arm i of said friction-lever is raised and the opposite end carrying the key-presser is depressed and in turn depresses the key. When 60 the length of the slot in the music has passed the beveled prong or toe a' of the lever a, the solid part of the music-sheet acts on the said toe again and presses it inward, whereby that 65 end of the lever h opposite the one acted upon by the spring h³ is depressed and the one acted upon by the spring is raised, and thus

the friction-lever k is raised from the friction-roller E and swung back in the inverse direction of the arrow x². The levers L can be adjusted vertically, so as to be in proper position for the key, and the key-pressers l' can be adjusted laterally, so as to be over the longitudinal central lines of the keys. In the construction shown in Figs. 5, 6, and 7 the casing A is mounted to slide on cleats P, secured to the piano-easing G. In this construction the shaft P has a cog-wheel V', engaging a pinion V on a crank-shaft N in the side of the piano-easing, as shown in Figs. 5 and 6. In this construction the cranks f² act on the standards g' of the levers h⁴, pivoted on a rail X, the opposite ends of said levers being pivoted to the friction-levers k. Each friction-lever is provided with an arm i', having a pivot m¹, on 85 which the forked end of a vertically-sliding push-bar l⁴ rests, the upper end P of which can press the inner end of the key F upward. A screw u, at the inner end of the key-lever, rests on a shoulder or abutment of the rod l⁴, 90 and serves for adjusting the key-lever in relation to said push-rod. Whenever an angle-lever snaps upward the friction-surface of the friction-lever k comes in contact with the roller E, the rod l⁴ is moved upward and acts 95 on the key, as shown in Fig. 5. The plates b b' are pivoted at e e and provided at their opposite ends with transverse slots d d, through which pins c c pass. These plates b b', to which said levers a are pivoted, permit 100 of aligning the prongs or toes a', according to the music-sheet in case the same has warped or contracted.

It is evident that the above-described mechanism can be used with a rotative music 105 sheet or disk, as well as with a longitudinally-movable sheet.

Having thus described my invention, I claim as new and desire to secure by Letters Patent—

1. In a mechanical playing attachment for playing key-instruments, the combination, with a key-presser, of a friction-lever connected with the same, a friction-roller adapted to act on the friction-lever, and mechanism, 115 substantially as herein shown and described, for moving the friction-lever toward or from the friction-roller, and a vertically-adjustable block in which the key-presser is pivoted, substantially as set forth.

2. In a mechanical playing attachment, the combination, with a key-presser, of a friction-lever connected with the same, a friction-roller adapted to act on the friction-lever, a screw-block in which the key-presser is pivoted, a screw screwed into said screw-block and serving for vertically adjusting said block, and mechanism, substantially as herein shown and described, for adjusting the friction-lever by the action of a perforated 125 music-sheet, substantially as set forth.

3. In a mechanical playing attachment, the combination, with the pivoted lever l, of a friction-lever connected with the same, a fric-

tion-roller adapted to act on the friction-lever, mechanism, substantially as herein shown and described, for shifting the friction-lever toward or from the friction-roller by the action of the perforated music-sheet, and a laterally-adjusting key-pressing head on one end of the lever *l*, substantially as set forth.

4. In a mechanical playing attachment, the combination, with a rail *B*², the adjustable plates *b b'*, pivoted on the same, angle-levers *h*, pivoted in said plates *b b'*, the rods *f*, the crank-rods *f'*, the levers *h*, the friction-levers *k*, the friction-roller *E*, and key-pressers actuated by said friction-lever, substantially as set forth.

5. In a mechanical playing attachment, the combination, with a rail *B*², of the pivoted plates *b b'*, resting flat upon the rail *B*² and pivoted to the same, a series of levers *a*, pivoted in said plates, key-pressers, and mechanism, substantially as herein shown and described, for operating the key-pressers, substantially as set forth.

In testimony whereof I have signed my name to this specification in the presence of two sub-
scribing witnesses.

EMIL CAPITAINE.
